United States Patent Office

Des. 225,275
Patented Nov. 28, 1972

225,275

GUITAR OR SIMILAR ARTICLE

Buck Owens, Bakersfield, Calif., assignor to Chicago
Musical Instrument Co., Lincolnwood, Ill.

Filed Feb. 11, 1971, Ser. No. 114,749

Term of patent 14 years

Int. Cl. D17—03

U.S. Cl. D56—1

FIG. 1 is a front perspective view of a guitar or similar article, showing my new design.

FIG. 2 is an elevational view showing the right side thereof.

FIG. 3 is an elevational view showing the left side thereof.

FIG. 4 is a rear perspective view thereof.

FIG. 5 is a bottom end view thereof.

The drawings are lined to show the colors red, white, blue and brown.

I claim:

The ornamental design for a guitar or similar article, substantially as shown and described.
